UNITED STATES PATENT OFFICE.

FRANK L. WHITE AND MARY G. SEMPLE, ADMINISTRATRIX OF JAMES SEMPLE, DECEASED, OF PITTSBURG, PENNSYLVANIA.

PIG-EJECTOR.

SPECIFICATION forming part of Letters Patent No. 650,596, dated May 29, 1900.

Application filed July 26, 1899. Serial No. 725,161. (No model.)

To all whom it may concern:

Be it known that FRANK L. WHITE and JAMES SEMPLE, of Pittsburgh, in the county of Allegheny and State of Pennsylvania, have 5 invented a new and useful Improvement in Pig-Ejectors, of which the following is a full, clear, and exact description, reference being had to the accompanying drawings, forming part of this specification, in which—

10 Figure 1 is a side elevation, partly in section, of the improved apparatus. Fig. 2 is a top plan view of the same, partly broken away. Figs. 3 and 4 are respectively a sectional side elevation and a vertical cross-section of the 15 controlling-valve and connections on a larger scale, and Fig. 5 is a detail view showing a modified arrangement of the motive cylinder.

The invention relates to the removing of 20 pigs from metal molds where these metal molds are arranged in an endless series passing over wheels at the ends; and its object is to provide apparatus which will insure the removal of the pigs and enable motive fluid to be applied for striking a blow, the supply of 25 fluid being controlled by the movement of the molds.

In the drawings, 22 represent the sprocket-wheels at the discharge end of a Uehling casting apparatus, and 33 the molds secured between the sprocket-chains passing over these wheels. Directly in front of this discharge end is provided motive cylinders 44, each having a piston-rod 5, provided at the front end with a block 6, within which is removably secured the pin 7, which strikes the pig in the mold. Each motive cylinder is mounted upon trunnions 88 and is provided with a depending web 9, which is normally held in vertical position by adjustable springs 10, these 35 springs returning the cylinder to its normal position whenever it is swung by the dragging action of the pigs upon the piston. The adjusting-screws 10' enable the point at which the blow is delivered to be adjusted as desired.

The fluid-supply exhaust-pipes 11 and 12 extend to the centers of the trunnions on opposite sides of the cylinder and there connect with pipes 13 and 14, leading into opposite 50 ends of the cylinder. Pipes 15 and 16 are bypasses leading from the pipes 13 and 14 and

arranged to cushion the piston at the ends of its stroke. The pipes 11 and 12 are alternately inlet and exhaust pipes, and they connect with the casing 17 of a rotary valve 18 in pairs located side by side, as shown in Fig. 3. The rotary valve 18 is loosely connected with and rotated by the shaft 19, to which the sprocket-wheels 2 are secured, and this valve contains the inlet-ports 20 and the exhaust-ports 21, 60 which coat with the ports 20' and 21' in the casing 17.

22 is the main fluid-supply pipe, which leads through the plate or head 23 of the valve, and 24 is the exhaust-pipe, leading from the hollow center of the disk. The entering fluid passes into an annular chamber 25 in the rear of the disk and thence is fed through the inlet-ports of the valve or disk 18 to the pipes 11 and 12, the exhaust passing back through these pipes and through the disk to the exhaust-port. The ports in the disk are so arranged that a quick back-and-forth motion will be given to the piston-rod of one cylinder and immediately after to the piston-rod 75 of the other cylinder, when a mold is directly in front thereof.

There are as many inlet and exhaust ports in duplicate as the number of molds mounted upon the carrier—a number equal to the mold-spaces in the circumference of wheels 22—so that two sharp successive blows will be delivered against the pigs in each mold as the molds successively reach a position in front of the striking pins.

Instead of cushioning the piston at the ends of its stroke by the fluid in the cylinder the piston-rod 5' may extend through both ends of the cylinder, as shown in Fig. 5, and be provided with spiral springs 26, which will 80 impinge upon the stuffing-boxes of the cylinder at each stroke and prevent jarring or injury to the parts.

Many changes may be made in the form and arrangement of the parts without departing from the invention.

What is claimed is—

1. The combination with a series of molds, of mechanism for supporting and moving said molds, and a pig-knocker located adjacent to the molds, a motive cylinder arranged to actuate the pig-knocker, and mechanism for op-

erating the valve controlling the fluid-supply to the cylinder, said mechanism being actuated by the means for causing the movement of the molds; substantially as described.

5 2. A traveling series of molds, an end wheel over which they move, a motive cylinder having its piston-rod arranged to act upon the pigs, and a valve device controlling the cylinder, and rotated by the wheel over which the molds travel; substantially as described.

10 3. The combination with an endless series of molds, of a pair of pig-knockers arranged

to act successively on each mold; substantially as described.

In testimony whereof we have hereunto set our hands.

FRANK L. WHITE.

MARY G. SEMPLE,

*Administratrix of the estate of James Semple,
deceased.*
